UNITED STATES PATENT OFFICE.

CLARE H. DRAPER, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

SHUTTLE-BOX TENSION-CONTROLLING MECHANISM FOR LOOMS.

Application filed August 23, 1922. Serial No. 583,782.

To all whom it may concern:

Be it known that I, CLARE H. DRAPER, a citizen of the United States, residing at Hopedale, in the county of Worcester and 5 State of Massachusetts, have invented certain new and useful Improvements in Shuttle-Box Tension-Controlling Mechanism for Looms; and I do hereby declare the following to be a full, clear, and exact description 10 of the invention, such as will enable others skilled in the art to which it appertains to make and use the same.

The present invention relates to an improvement in shuttle box tension controlling mechanism for looms.

The object of the invention is to produce a construction for varying the resistance with which the shuttle is received in the shuttle box to which it is thrown with the 20 position of the lay. To the above ends the present invention consists in the shuttle box tension controlling mechanism for looms hereinafter described and particularly defined in the claims.

25 In the accompanying drawings illustrating the preferred form of the invention, Fig. 1 is a perspective view of the end of a lay provided with the invention; Fig. 2 is a longitudinal vertical section taken through the 30 pivot of the binder; and Figs. 3 and 4 are diagrams illustrating the operation of the device.

The illustrated embodiment of the invention is described as follows: The lay 1 is 35 provided with the usual shuttle box, the box plate 2 of which is shown. The picker stick 3 is supported in the lay in the usual manner. The picker strap 4 embraces the picker stick. The binder 5 is pivoted on the 40 lay, being normally pressed in a direction to cause it to engage the shuttle by the auxiliary binder spring 6. The pivot pin 7 upon which the binder 5 is pivoted is provided with an eccentric portion 8, which is received in a bushing in the binder. By turning 45 the binder pivot pin 7 on its axis, the position of the eccentric portion 8 will be changed, and therefore the position of the surface of the binder will be changed and the frictional resistance which the lay offers to the entrance of the shuttle to the box will be varied. The binder pin 7 is mounted 50 in the lay so as to be capable of turning therein, the lay being provided with a bush-

ing 9 in which the pivot pin turns. The upper end of the pivot pin 7 has secured to it a lever 10 which extends first rearwardly and thence toward the frame of the loom where its end is received in the fork 11 attached to the frame. Now, as the lay beats back and forth, the end of the pivot pin operating lever 10 being held in the fork from movement, the pivot pin is turned and the eccentric 8 is turned, and thereby the position of the surface of the binders vary with the movements of the lay so as thereby to increase the tension on the binders as the lay beats toward the back center, and to decrease the same as the lay beats forward. By reference to Figs. 3 and 4 it will be seen 70 that with the lay in forward position the parts would occupy a relative position such as shown in Fig. 3, with the binder retracted, but that when the lay was on the back center the parts would occupy a position 75 like that shown in Fig. 4, with the eccentric portion 8 moved forward so as to cause the binder to exert a greater pressure upon the shuttle. It is to be understood in this connection that the eccentricity of the eccentric portion 8 is accentuated in drawing by exaggeration for the purpose of clearness of illustration. The arrangement is such that the surface of the binder at the pivot is moved forward slightly when the lay is in 85 its rearmost position, so as to cause the binder to engage the shuttle with the greatest resistance on the back center, and with less and less resistance as the lay moves forward.

90 The invention disclosed herein is broadly claimed in the application of Clare H. Draper filed July 11, 1922, Serial No. 574,212.

Having thus described the invention, what 95 is claimed is:

1. Shuttle box tension controlling mechanism for looms having, in combination, a lay, a shuttle box carried by the lay and provided with a binder, an eccentric pivot 100 for the binder, and means for oscillating the pivot with the beats of the lay to increase the pressure of the binder on the lay as the lay moves rearwardly, and to decrease the same as the lay moves forwardly.

2. Shuttle box tension controlling mechanism for looms having, in combination, a lay, a shuttle box carried by the lay and pro-

vided with a binder pivoted at one end on the lay, and means for varying the position of the binder pivot during the operation of the loom to increase and decrease the pressure of the binder on the shuttle in accordance with the position of the lay.

3. Shuttle box tension controlling mechanism for looms having, in combination, a

lay, a shuttle box carried by the lay and provided with a binder pivoted at one end ¹⁰ on the lay, and means for varying the position of the binder pivot during the operation of the loom to decrease the pressure of the binder on the shuttle as the lay moves forwardly.

CLARE H. DRAPER.
